Primary Examiner — Catherine Tuttle(74) *Attorney, Agent, or Firm* — Griffiths & Seaton PLLC; JoAnn M. Seaton**CLAIM**

The ornamental design for a toy, as shown and described.

DESCRIPTION

FIG. 1 is a top and front perspective view of a toy showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view.

The broken lines are included for the purpose of illustrating optional through holes and surface ornamentation that form no part of the claimed design.

1 Claim, 7 Drawing Sheets(56)
